UNITED STATES PATENT OFFICE.

JONAS M. KILMER, OF BINGHAMTON, NEW YORK.

HORSESHOE.

SPECIFICATION forming part of Letters Patent No. 254,337, dated February 28, 1882.

Application filed August 23, 1881. (No model.)

To all whom it may concern:

Be it known that I, JONAS M. KILMER, a citizen of the United States, resident of Binghamton, in the county of Broome and State of New York, have invented a new and valuable Improvement in Horseshoes; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a bottom view of my invention. Fig. 2 is a cross-section, and Fig. 3 is a longitudinal section.

This invention has relation to horseshoes; and it consists in the novel construction and arrangement of two rabbeted portions provided with registering upwardly-tapering holes and connected by a pivot-pin, also tapering upwardly and upset at its upper or smaller end, as will be hereinafter fully described, and pointed out in the claim.

Referring by letter to the accompanying drawings, A designates a sectional horseshoe. One section, B, carries the toe-calk C, has a rabbet, D, and has a shoulder, E, under-beveled, as shown. The other section, F, has a rabbet, G, and a shoulder, H, having an under bevel, as shown. The rabbet D of the section B is made in the upper face of the section, and is in its extent about the length of the toe-calk. The shoulder E is concave, and the end of this section is convex, as shown. The rabbet G of the section F is in the under face thereof. The end of the section F is convex, and its shoulder H is concave, so that when the sections are united the convexities of the one fit the concavities of the other section. When the sections are joined, the rabbets lapping, and the curves of the shoe are in line, a tapering hole, I, is bored from the bottom of the shoe, in rear of the toe-calk, up through both of the sections. In this hole I a tapering pin, J, is inserted from the bottom, and is upset at the upper and smaller end to form the pivot for the sections of the shoe. The object of the

pivot is to permit the shoe to be adjusted to hoofs of different sizes. It is made tapering 50 from below upward, in order that as the under face of the shoe and pivot become worn the pivot cannot drop out or the under section of the shoe become detached. This latter result is obtained for the reason that the tapering 55 hole and tapering pin coincide throughout, and the wearing away of the lower end of the pivot-pin does not destroy the head, as it continually forms a new head.

The sections B and F are each made in one 60 piece, being struck up by dies. The toe-calk therefore forms an integral part of section B, and serves to strengthen the shoe at the junction of the sections. In summer time and where light shoes are required I may dispense 65 with the toe-calk. The principal object I accomplish is to prevent the contraction of the animal's hoof. The pivot-point is of such construction, the curves fitting each other so that the sections may be worked both inwardly and 70 outwardly, that when the weight of the animal comes upon the shoe it will expand and will permit the hoof to retain its natural growth.

Having thus fully described my invention, 75 what I claim as new, and desire to secure by Letters Patent, is—

In a sectional horseshoe, the combination of the section B, having the toe-calk C, rabbet, and under-beveled shoulder E, and the section 80 F, having rabbet G and under-beveled shoulder H, the ends of said sections being convex and the shoulders concave, the said sections being pivoted together through the media of the tapered registering holes I I' and the tapering 85 pin J, passed up through said holes and upset at its smaller end, substantially as and for the purposes specified.

In testimony that I claim the above I have hereunto subscribed my name in the presence 90 of two witnesses.

JONAS M. KILMER.
